United States Patent Office

Des. 215,469
Patented Sept. 30, 1969

215,469

CASSEROLE

Gerald Gulotta, New City, N.Y., assignor to Block China
Company, New York, N.Y., a partnership

Filed Dec. 16, 1968, Ser. No. 14,986

Term of patent 14 years

Int. Cl. D7—01

U.S. Cl. D44—15

FIG. 1

FIG. 2

FIG. 3

FIG. 4

FIG. 5

I claim:

The ornamental design for a casserole, substantially as shown.
